UNITED STATES PATENT OFFICE.

JULIUS HOFMEIER, OF VIENNA, AUSTRIA-HUNGARY.

EMBOSSING-ROLLER.

SPECIFICATION forming part of Letters Patent No. 615,703, dated December 13, 1898.

Application filed July 6, 1896. Serial No. 598,179. (No model.)

To all whom it may concern:

Be it known that I, JULIUS HOFMEIER, a subject of the Emperor of Austria-Hungary, residing at Vienna, in the Empire of Austria-Hungary, have invented new and useful Improvements in Embossing-Rollers, of which the following is a specification.

The invention has been patented in England, No. 16,222, dated August 25, 1894; in Germany, No. 82,530, dated August 26, 1894; in France, No. 240,984, dated August 25, 1894; in Belgium, No. 111,550, dated August 25, 1894; in Russia, No. 425, dated November 28, 1897, and in Austria-Hungary, No. 6,514/15 5,722, Registerband 44.

My invention is an improved embossing-roller; and it consists of the features herein-after described, and particularly pointed out in the claims.

Figure 1 is a cross-section of the plate containing the design. Fig. 2 is a side view of the same. Fig. 3 shows the plate bent ready to be placed on the roller. Fig. 4 is a cross-section; Fig. 5, a perspective view of the roller 20 on which the plates are placed. Fig. 6 shows a cross-section of the roller with the plate placed on it. Fig. 7 is a view of the plate fastened on the roller with parts in section. Fig. 8 is a side view of the rolling-mill in 25 which the roller is used.

The leather the grain of which is to be reproduced is covered on its grain side with a coating which is a good conductor of electricity, and a thin layer of metal is then precipitated thereupon in the galvanic way in the electrolytical bath. Care is to be taken that the coating be not thicker than two or three millimeters, as otherwise when afterward the plate is bent the design of the grain reproduced thereupon would be distorted. To the 30 back side of the head end of the metallic plate *a* prepared in this way, Figs. 1 and 2, close to the border, an iron transverse rail *b* is riveted or otherwise secured. The plate is then 35 bent round on a plate-bending machine, Fig. 3, and applied to a roller *c*, Figs. 4 and 5, susceptible of being heated inside and provided with a transverse groove *d*, extending parallelly to the longitudinal axis of the roller. 40 The transverse rail *b* is engaged in the groove *d* and fastened therein by means of screws, while the whole remaining part of the plate

lies loosely upon the roller, so that it may freely expand under the action of heat, Fig. 6.

The roller is of such diameter that it is not 55 completely inclosed by the plate. There remains, therefore, between the groove *d* and the free end of the plate a free intermediate space *x*, Fig. 6, permitting the plate to expand without covering with its free end the groove *d* or the rail *b*. The plate being fastened, as above described, only on one end to the roller, its free end would spring off as often as it had passed the counter-roller. To 60 avoid this, rings *e* are pushed over or fixed to the front sides of this roller, Fig. 7, holding down the said plate to the roller without raising obstacles to its expansion in the longitudinal and lateral direction. The roller is then placed in an ordinary roller-press. The counter-roller *f* of this press has its front ends at 65 *g* turned off, affording the rings *e*, pushed upon the roller *c*, the necessary space.

In working the paper or the like is passed through between the revolving rollers. The 70 roller *a* is revolved in such a manner that the place where the rail *b* is arranged comes first against the roller *f*.

I claim—

1. An embossing roller or cylinder having 80 an embossing-plate fixed thereto along one extremity leaving the other extremity free and the hollow rings around the edges of the embossing-plate confining the same loosely in order to prevent the free extremity of the 85 plate from leaving the cylinder, substantially as described.

2. An embossing roller or cylinder having 90 an embossing-plate fixed thereto along one extremity leaving the other extremity free and the hollow rings around the edges of the embossing-plate confining the same loosely in order to prevent the free extremity of the plate from leaving the cylinder, said plate being secured to the roller by a bar on one 95 edge of the plate fitting in a groove in the roller, substantially as described.

In testimony whereof I have signed my name to this specification in the presence of two subscribing witnesses.

JULIUS HOFMEIER.
